CLAIM

The ornamental design for a temperature transmitter housing, as shown and described.

DESCRIPTION

FIG. 1 is a perspective view showing the top, rear and right side of a temperature transmitter housing showing our new design;

FIG. 2 is a front elevational view thereof;

FIG. 3 is a right side elevational view thereof;

FIG. 4 is a left side view thereof;

FIG. 5 is a rear elevational view thereof; and,

FIG. 6 is a top plan view thereof.

The bottom of the temperature transmitter housing is unadorned.
